UNITED STATES PATENT OFFICE.

RUSSELL SINCLAIR, OF SYDNEY, NEW SOUTH WALES, AUSTRALIA.

SUBMARINE VESSEL OR DIVING APPARATUS.

SPECIFICATION forming part of Letters Patent No. 728,031, dated May 12, 1903.

Application filed November 24, 1902. Serial No. 132,649. (No model.)

To all whom it may concern:

Be it known that I, RUSSELL SINCLAIR, consulting mechanical engineer, a subject of the King of Great Britain, residing at No. 97 Pitt street, in the city of Sydney and State of New South Wales, in the Commonwealth of Australia, have invented new and useful Improvements in Submarine Vessels or Diving Apparatus, of which the following is a specification.

This invention relates to submarine vessels or diving apparatus for working upon the sea-bottom, and it has been specially devised in order that such vessels or diving apparatus may be easily and efficiently propelled along the bottom and has particular reference to such submarine vessels or diving apparatus as form the subject-matter of United States Patents of the Pacific Pearl Fishing Company, Limited—namely, No. 581,174, dated April 20, 1897, and No. 622,529, dated April 4, 1899; yet while being so applicable to the prior inventions just before mentioned these present improvements may be applied to other submarine vessels or diving apparatus adapted to be propelled along the sea-bottom by manual or other power inclosed within the hull.

These improvements consist in the combination, with the casing or shell or hull of the submarine vessel or diving apparatus, of devices or what may be termed "grasshopper-legs" at the side and about midway or just forward of midway of the hull. Each grasshopper-leg consists of a pedal or fork or other form of foot attached to legs or levers connected with a radius bar or lever on the end of a shaft or spindle passing through the interior of the hull. These bearings may have stuffing-boxes or glands or ground ball-joint, but at any rate are water-tight. On the inner end of the spindle is carried an operating lever or handle which may be worked by manual or other power.

In order that this invention may be clearly understood, reference will now be made to the drawings herewith, in which—

Figure 1 is a longitudinal elevation of a submarine vessel or diving apparatus constructed in accordance with the specifications attached to the patents hereinbefore referred to and having these present improvements

attached; and Fig. 2 is a cross-sectional elevation of the same, showing only these present improvements.

The grasshopper-legs are affixed as herein to the hull 3 on either side and opposite to one another. As the construction of each is identical but one will be referred to, though both will bear the figures of reference. Bolted or riveted to said hull 3 is a bracket 4, having internally a stuffing-box 5 and a gland 6 kept tight on the packing in said box 5 by thimble-nut 7. Externally this bracket 4 has a ball-cup 8 and a keeper-nut 9, which latter has a stuffing-box 10 and gland 11, tightened up by nuts 12. Through the stuffing-boxes the spindle 13 passes, a collar 14 thereon having bearing on balls in cup 8. On the inside this spindle 13 has a square or key end for a crank-handle 15 or other device for operating it, or the spindle 13 may pass from side to side with one or more cranks between the brackets 4. On the external end of the spindle is keyed the lever or radius-bar 16, knuckle-jointed at 17 to leg or thrust-bar 18, reaching below the bottom of the hull 3. The leg 18 has a foot or feet adapted to grip upon the ground, and, preferably, these are constructed, as shown, of a series of combs or teeth 19 of some width firmly affixed to said legs by bolts 20. In some cases, according to the nature of the sea-bottom, it might be desirable to affix on or under the hull 3 rollers or wheels fore and aft or skids or other devices to support its weight and to ease its progress.

Reciprocating motion is imparted by manual or other power to the crank-handle 15 by operators inside the hull in such a way that, the foot 19 of the grasshopper-leg 18 taking upon the sea-bottom, the hull 3 will be pushed forwardly—that is to say, in an opposite direction to the motion of the inside handle—being partially lifted at the same time at front, so that it makes progress in a kind of hop. The reverse motion of the handle or lever moves the foot 19 of the grasshopper 18 forwardly, so that a fresh grip of the sea-bottom may be made.

Having now particularly described and ascertained the nature of my said invention and in what manner the same is to be performed, I declare that what I claim is—

1. The combination with a submarine ves-

100

sel of grasshopper-legs or thrust-bars jointed to radius-levers adapted to be operated inside said vessel to travel the same in a series of hops substantially as herein described and explained.

2. The combination with a submarine vessel adapted to support itself on a sea-bottom of grasshopper-legs having thereon feet or ends adapted to hold and be thrust against said sea-bottom and move the vessel in a series of hops substantially as herein described and explained.

3. The combination and arrangement with a hull 3 of a bracket 4 having stuffing-box 5 gland 6 nut 7 ball-cup 8 nut 9 stuffing-box 10 gland 11 and nuts 12 and a spindle 13 having a collar 14 as and for the purposes set forth

substantially as herein described and explained and as illustrated in the drawings.

4. The combination and arrangement with a hull 3 a shaft 13 having collar 14 and a suitable water-tight support and bearing for such shaft 13 of radius-lever 16 knuckle-joint 17 and leg 18 having suitable holding-foot as and for the purposes set forth substantially as herein described and explained and as illustrated in the drawings.

In testimony whereof I have signed my name to this specification in the presence of two subscribing witnesses.

RUSSELL SINCLAIR.
